ALFRED A. ANDERSON, OF GALESBURG, ILLINOIS.

Letters Patent No. 72,440, dated December 24, 1867.

IMPROVED MORTAR-MILL.

The Schedule referred to in these Letters Patent and making part of the same.

TO ALL WHOM IT MAY CONCERN:

Be it known that I, ALFRED A. ANDERSON, of Galesburg, in the county of Knox, and State of Illinois, have invented certain new and useful Improvements in Machines for Mixing Mortar; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention consists of a machine for grinding and mixing mortar for use in building walls, plastering buildings, &c., as hereinafter described.

Figure 1 represents a side elevation, with a portion of the case broken away to exhibit the internal arrangement.

Figure 2 is a rear-end view; and

Figures 3 and 4 views of different forms of the grinding and mixing-rolls.

In preparing mortar for use, either in laying up walls or for plastering the walls and ceilings of buildings, it is customary to incorporate or mix the ingredients by hand, which is a slow and laborious process. The object of my present invention is to provide a machine for doing this work, whereby the labor may be lessened and the operation greatly expedited.

To accomplish this object, I provide a cylindrical metallic case, A, more or less conical, as represented in fig. 1, and mount it upon a suitable frame, D, which should be provided with axles for mounting the machine on wheels, for conveying it from place to place, as required, for use. Upon this case, near its rear or larger end, is secured a hopper, B, for receiving the materials to be mixed, there being an opening at the bottom of this hopper, through into the case A, to permit the material to pass to the grinding and mixing-apparatus located within.

The grinding and mixing-apparatus consists of a spirally-grooved or fluted roller, C, of such a size as nearly to fill the interior of the case A, it being made conical to correspond therewith, and mounted on journals at each end, so as to revolve freely in the case. Upon the end of the journal, at the rear end of the machine, is secured a gear-wheel, b, which gears into a pinion, e, mounted in the frame by its side; and by means of a handle or crank, h, motion is imparted to the pinion e, and thereby to the cylinder C, which is thus made to revolve in such a direction as that the grooves or flanges, while thoroughly grinding and mixing the material fed in at the hopper, shall at the same time work the same forward to the front or smaller end of the cylinder, where it passes out through an opening in the lower side of the case, as represented in fig. 1.

Instead of the spirally-grooved roller C, other forms may be used, and for some kinds of mortar may be preferable. In fig. 3 is represented a modification of the grinding-cylinder, which consists of a plain conical roller, I, having a series of radial flanges projecting from its surface and arranged spirally thereon, as shown; or it may consist of a central shaft having heads E F secured at its opposite ends, with a series of plain, grooved, or spiral rolls, as represented by *ill*, fig. 4, secured thereto in such a manner as to revolve on their journals in said heads E and F; these various forms being used as may be preferred.

In order to permit of the ready removal and changing of the different styles of grinding-cylinders, the rear end, A', of the case A is made removable, it being held in place by means of pivoted latches or bars n on opposite sides of the case, which hook over projecting lugs on the end piece A'.

It is of course obvious that the machine may be operated by animal or steam-power instead of hand-power, and that it may be made of any required size, to adapt it for use on a large or small scale, as required.

Having thus described my invention, what I claim, is—

A mortar-mixing machine, consisting of the case A, provided with a hopper, B, detachable end piece A', and the gear-wheels b c, arranged to operate a grinding or mixing-cylinder placed within the hopper, the whole constructed and mounted on a carriage, substantially as described.

ALFRED A. ANDERSON.
